REFRIGERATING APPARATUS

Bo Folke Randel, San Diego, Calif.

Application January 27, 1936, Serial No. 60,966

1 Claim. (Cl. 62—115)

(Granted under the act of March 3, 1883, as amended April 30, 1928; 370 O. G. 757)

This invention relates to refrigerating means and methods and is an improvement upon the invention disclosed in applicant's copending application Serial No. 477,038.

According to the present invention, an atomized liquid at high velocity is employed as a motive medium to exhaust an evaporating space and transfer a refrigerant vapor from a low pressure space to a high pressure space. The capacity of the apparatus will by this arrangement be considerably increased, due to more thoroughly commingling of the vapor and liquid. The preferred method is to employ the same medium in liquid and vapor state both as a motive medium and as a refrigerant, but different mediums may be used if so desired. In the event two different mediums are employed they should be of different specific gravities so that they will separate after liquefaction into separate bodies.

With these and other objects in view, as well as other advantages that may be incident to the use of the improvements, the invention consists in the parts and combinations thereof herein-after set forth and claimed, and with the understanding that the several necessary elements constituting the same may be varied in proportion and arrangement without departing from the nature and scope of the invention, as defined in the appended claim.

In order to make the invention more clearly understood, there are shown in the accompanying drawing, means for carrying the invention into practical use, without limiting the improvements in their useful application to the particular construction, which, for the purpose of explanation, have been made the subject of illustration.

In the accompanying drawing:

Fig. 1 is a diagrammatic view partly in side elevation and partly in vertical section of a refrigerating apparatus embodying the invention;

Fig. 2 is a vertical sectional view on a larger scale through the atomizer shown in Fig. 1; and

Fig. 3 is a similar view of a modified form of atomizer.

Referring to the drawing and particularly to Figs. 1 and 2 thereof, a refrigerating apparatus constructed in accordance with the invention is shown as comprising a high pressure receiver 10 for containing a supply of liquid employed both as a motive medium and as a refrigerant and having a cooling coil 11 suitably mounted therein. A conduit 12 extends through the wall of the receiver 10 adjacent to the bottom thereof and communicates at its outer end with a suitable

pump 13 driven by an electric motor 14. The motive medium is drawn from the receiver 10 by the pump 13 and forced upwardly at relatively high pressure through a pipe 15 and thence back into the receiver 10 through an atomizer, indicated generally at 16, located on the upper end of the receiver.

The atomizer 16 preferably comprises an elbow fitting 17 which communicates with the pipe 15 and which is secured to the upper end of a casting 18 having a Venturi tube portion 19 and an upper chamber 20 communicating therewith. An annular flange 21 is disposed within the chamber 20 (Fig. 2) and supports a disk 22 having a plurality of very small openings 23 formed therein and which is maintained against displacement by a retainer ring 24. The apparatus also includes a refrigerating coil 25 which communicates at its lower end with the chamber 20 and at its upper end through a reduction valve 26 with a pipe 27 communicating with the high pressure receiver 10 adjacent to its lower end.

In operation, the liquid motive medium is drawn from the receiver 10 by the pump 14 and forced upwardly through the pipe 15 and thence into the upper portion of the atomizer 16, in this case the elbow 17. The liquid under pressure then passes through the apertures 23 in the disk 22 and travels toward the Venturi portion of the atomizer at high velocity in the form of a large number of jets each consisting of a series of very minute droplets closely resembling vapor. These jets of liquid draw the refrigerant from the lower end of the coil 25, commingles with it and forces the same through the restricted portion 19 of the Venturi tube and back into the pressure tank 10. This movement of the liquid motive medium develops a negative pressure within the chamber 20 such as will draw liquid employed as the refrigerant from the receiver 10, through the pipe 27 valve 26 and cooling coil 25 into the chamber 20 where it is entrained by the liquid motive medium in jet or atomized form and is carried thereby back into the receiver 10. During the passage of the liquid motive medium through the orifices 23 and the Venturi tube it is subjected to both friction and compression which action will cause a certain degree of heat to be generated which will be extracted through contact with the cooling coil 11, causing the condensation of the refrigerant entrained by the atomized liquid motive medium. The action above described is comparable to that of a steam jet compressor, but without the necessity of extraneous heat.

If the liquid motive medium is of greater spe-

specific gravity than the refrigerant, it will collect in the lower portion of the receiver 10 while the condensed refrigerant will collect in a superimposed layer or stratum.

5 In this case the expansion valve 26 may be dispensed with and the pipe 21 connected with the receiver 10 above the level of the liquid motive medium.

In Fig. 3 an atomizer of slightly different type 10 is shown. In this particular construction the refrigerant is drawn into the atomizer through a pipe 28 which communicates with the cooling coil 25 and which passes through a packing gland 29 formed on the upper portion of the elbow 17 and centrally through the perforated disk 22.

15 While the primary object is to devise a refrigerating means and method, the specific atomizer and pump action thereof may also be employed in other applications, as for instance, as vacuum 20 pumps in heating installations or as a pump when it is desired to move a vapor or a gas from a lower to a higher pressure or from one space to another.

Other modifications and changes in the proportions and arrangement of the parts may be 25 made by those skilled in the art without departing from the nature and scope of the invention as defined in the appended claim.

The invention described herein may be manufactured and used by or for the Government of the United States of America for government purposes without the payment of any royalty thereon or therefor.

I claim:

In a refrigerating apparatus a receiver for containing a supply of liquid refrigerant; a Vent tube communicating with said receiver above the liquid level of the refrigerant therein; an atomizer injector communicating with said Vent tube; a refrigerating coil communicating at one end with said receiver below the liquid level of said refrigerant and at its other end with said Venturi tube; and a pump for withdrawing a portion of said refrigerant from said receiver and delivering it under pressure to said atomizer injector and thence in a fine spray to said Vent tube and into the upper portion of said receiver, thus reducing the pressure in said refrigerating coil so as to cause another portion of said refrigerant to be withdrawn from said receiver, circulated through said coil, entrained and commingled with said spray and delivered back to said receiver in an atomized condition.

BO FOLKE RANDI
